United States Patent Office

Des. 188,448
Patented July 19, 1960

188,448

COMBINED FOOD COOKER, SERVER, AND CABINET

Harry S. Freiberg, 8808 Alcott, Los Angeles, Calif.

Filed Mar. 23, 1959, Ser. No. 55,108

Term of patent 7 years

(Cl. D81—10)

Fig. 1.

Fig. 2.

Fig. 3.

Fig. 1 is a front perspective view of a combined food cooker, server and cabinet, showing my new design.

Fig. 2 is a top plan view thereof.

Fig. 3 is a front elevation thereof.

Fig. 4 is a front perspective view of the combined food cooker, server and cabinet, with the end and top parts thereof in extended position.

Fig. 5 is a top plan view of Fig. 4.

Fig. 6 is a front elevational view of Fig. 4.

The back of the combined food cooker, server and cabinet is substantially plain in both closed and open position.

I claim:

The ornamental design for a combined food cooker, server and cabinet, as shown and described.
